UNITED STATES PATENT OFFICE.

JOSEPH BOTT, OF ROCHESTER, NEW YORK, ASSIGNOR TO BASTIAN BROS. COMPANY, OF ROCHESTER, NEW YORK, A CORPORATION.

BADGE OR BUTTON.

1,331,611.

Specification of Letters Patent. Patented Feb. 24, 1920.

Application filed July 10, 1919. Serial No. 309,876.

To all whom it may concern:

Be it known that I, JOSEPH Bott, a citizen of the United States, and resident of Rochester, in the county of Monroe and State 5 of New York, have invented certain new and useful Improvements in Badges or Buttons, of which the following is a specification.

The present invention relates to a badge 10 or button and more particularly to the manner of securing a fastening device to the badge or button, an object of this invention being to provide a construction in which the fastening device is not only firmly secured 15 to the badge or button against accidental displacement, but is also held against turning movement on the badge or button.

To this and other ends the invention consists of certain parts and combinations of 20 parts, all of which will be hereinafter described, the novel features being pointed out in the appended claims.

In the drawings:

Figure 1 is a front face view of the badge 25 or button;

Fig. 2 is a rear face view;

Fig. 3 is an enlarged section on the line 3—3, Fig. 2;

Fig. 4 is an enlarged section on the line 30 4—4, Fig. 2; and

Fig. 5 is a detail view of the fastening device.

Badges or buttons have been formed heretofore of sheet metal plates with collets 35 under which a fastening device has been received, but such constructions have been defective due to the fact that the fastening devices were not permanently secured to the button body and the latter would turn on 40 the fastening device. According to this invention, the fastening device is secured to the button body in such a manner that it cannot become accidentally disconnected from the body and the body is held against 45 turning on the fastening device.

Referring more particularly to the drawings wherein one embodiment of the invention is illustrated, 1 indicates the circular front plate of the button or badge which has 50 at its edge a rearwardly turned annular flange 2 deflected slightly inwardly. This

front plate is covered by a sheet of celluloid 3 or other material held in place on the front plate by a collet 4.

The collet is of annular form and is made 55 of sheet metal, its outer edge being received within and held by the rearwardly and inwardly turned flange and its inner edge being turned or bent forwardly at 5 substantially in abutment with the rear face of the 60 front plate to provide a substantially closed annular space 6 for the reception of the fastening device. This forwardly turned portion at the inner edge of the collet is deflected away from the rear face of the 65 front plate at two diametrically opposite points indicated at 7. The fastening device as illustrated in Fig. 5 is formed from a single piece of wire stock and has portions 8 received within the annular space formed 70 by the collet. A U shaped portion 9 between the ends of the wire stock is bent to project from the annular space under one of said deflected portions 7 to provide an anchor for the pin 10 of the fastening device. A pin 10 is formed by one of the extreme ends of the wire and projects through 75 the other deflected portion 7 of the collet.

By this arrangement the side walls of the deflected portions 7 of the collet coöperate 80 with the pin 10 and the U shaped portion 9 to prevent the turning of the fastening device in the collet. At the same time, the portions 8 of the fastening device are housed due to the fact that the inner edge of the 85 collet projects forwardly substantially to the forward face of the fastening device thus holding the fastening device against accidental removal.

What I claim as my invention and desire 90 to secure by Letters Patent is:

A badge or button comprising a circular front plate having a rearwardly and inwardly turned annular flange, an annular collet formed of sheet metal and having its 95 outer edge received within and held by the flange of the front wall and its inner edge turned forwardly substantially into abutment with the rear face of the front plate to provide a substantially closed annular 100 space, the forwardly turned inner edge having, at two diametrically opposite points,

portions deflected away from the rear face of the front plate, and a fastening device formed of a single piece of wire stock and having portions received and held within the 5 annular space by the forwardly turned inner edge of the collet, a portion between its ends bent to project from the annular space under

one of said deflected portions of the collet to provide an anchor, and a portion at one end extended through the space below the other deflected portion of the collet to provide a pin which is adapted to engage with the anchor.

JOSEPH BOTT.
